UNITED STATES PATENT OFFICE.

JOHN JAMES SHEPARD, OF DARLINGTON, SOUTH CAROLINA.

DESIGN FOR A CORSET-CASE.

SPECIFICATION forming part of Design No. 26,294, dated November 17, 1896.

Application filed September 28, 1896. Serial No. 607,261. Term of patent 14 years.

To all whom it may concern:

Be it known that I, JOHN JAMES SHEPARD, a citizen of the United States, residing at Darlington, in the county of Darlington and State 5 of South Carolina, have invented a new and original Design for a Corset Case or Cabinet, of which the following is a specification.

This invention relates to a new and original design for corset cases or cabinets; and 10 it has for its object to provide a design of this character that shall be both useful and ornamental.

The leading feature of the design resides in a case or cabinet of a cubical form, and 15 having a flat square top and bottom, ornamental beaded vertical corner-posts connecting the top and bottom, a plurality of square parallel shelf-pieces fitted to the corner-posts and arranged between the square 20 top and bottom of the case or cabinet, vertical parallel partition-strips extending from side to side of the case or cabinet between each pair of parallel shelf-pieces, whereby the ends of said strips and the adjacent edges of 25 the shelf-pieces will form a series of horizontally-aligned rectangular openings at each of the four sides of the case or cabinet, and a series of horizontal plain rectangular panels arranged at each side of the case or cabinet 30 and closing the spaces between alternate pairs of shelf-pieces, so as to alternate with the horizontally-aligned rectangular openings at each side of the case or cabinet.

In the drawings, Figure 1 is a perspective 35 view of a corset case or cabinet embodying the herein-described design. Fig. 2 is a horizontal sectional view thereof.

Referring particularly to the drawings, the numeral 1 designates a case or cabinet of a 40 cubical form and having the parallel flat top and bottom pieces 2 and 3, respectively. The flat top and bottom pieces 2 and 3 of the case or cabinet are of a square shape, and the flat top piece 2 is bounded at its edges by orna-

mentally-scalloped molding-strips 4, which 45 impart an ornamental appearance to the top of the case or cabinet. The squared top and bottom pieces of the case or cabinet are connected by vertical corner-posts 5, which corner-posts are provided with ornamentally- 50 grouped circular beads 6 and elongated convexed portions 7 between certain of said beads, and said corner-posts 5 have fitted thereto a plurality of square parallel shelf-pieces 8, arranged at regularly-spaced distances apart between the flat top and bottom pieces of the case or cabinet. The square parallel shelf-pieces 8 support vertical parallel partition-strips 9, extending from side to side of the case or cabinet between each pair 60 of shelf-pieces, so that the ends of said strips and the adjacent edges of the shelf-pieces will form a series of horizontally-aligned rectangular openings 10 at each of the four sides of the case or cabinet, and a series of horizontal 65 plain rectangular panels 11 close the spaces between alternate pairs of shelf-pieces, so as to alternate with said horizontally-aligned series of rectangular openings at each side of the case or cabinet. The panels 11 are of the 70 same length as the width of the sides of the case or cabinet, so as to completely close the spaces alternating with the rectangular openings 10, and at its base at two of its diametrically opposite sides the case or cabinet 1 75 has arranged therein a pair of rectangular drawers 12.

What I claim is—

The design for a corset case or cabinet herein shown and described. 80

In testimony that I claim the foregoing as my own I have hereto affixed my signature in the presence of two witnesses.

JOHN JAMES SHEPARD.
